UNITED STATES PATENT OFFICE

EMMETT BARKLEY, OF CHATTANOOGA, TENNESSEE

DESIGN FOR A COMBINED LAMP STAND AND PLANT HOLDER

Application filed May 7, 1931. Serial No. 39,754. Term of patent 3½ years.

To all whom it may concern:

Be it known that I, EMMETT BARKLEY, a citizen of the United States, residing at Chattanooga, in the county of Hamilton and State of Tennessee, have invented a new, original, and ornamental Design for a Combined Lamp Stand and Plant Holder, of which the following is a specification, reference being had to the accompanying drawings, forming part thereof, in which—

combined lamp stand and plant holder, showing my design,

The surface of the article is studded with small varicolored stones.

I claim:

The ornamental design for a combined lamp stand and plant holder, as shown and described.

EMMETT BARKLEY.
